(57) **CLAIM**

The ornamental design of a female thumb head figurine, as shown and described.

DESCRIPTION

FIG. 1 is a front, perspective view of the female thumb head figurine showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines represent an exemplary environment of use of the female thumb head figurine, and form no part of the claimed design.
